(57) **CLAIM**

The ornamental design for a satellite antenna, as shown and described.

DESCRIPTION

FIG. 1 is a top left perspective view of a satellite antenna showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top right front perspective view thereof;

FIG. 9 is a bottom rear left perspective view thereof; and,

FIG. 10 is a top left front perspective view thereof.

The dashed broken lines illustrate portions of the satellite antenna and form no part of the claimed design.
